UNITED STATES PATENT OFFICE.

GUIDO HORN, OF BERLIN-WEISSENSEE, GERMANY.

JACK FRAME OR SPOOLING MACHINE.

Application filed October 6, 1923. Serial No. 666,983.

To all whom it may concern:

Be it known that I, Guido HORN, engineer, a citizen of the Deutsches Reich, and resident of Berlin-Weissensee, Germany, have 5 invented certain new and useful Improvements in Jack Frames or Spooling Machines, of which the following is a specification.

In jack frames or spooling machines the 10 thread coming from delivery spool or reel is passed over a thread guide which to obtain a more uniform thread tension acts upon the brake of the reel or spool in such a manner that the brake is released in a degree 15 corresponding to the tension of the thread. Further it is well known to have a thread guide acting upon the drive of the spool spindle so that the drive is stopped as soon as the thread is finished, breaks or its 20 free delivery is impaired.

The object of the present invention is to provide a jack-frame or spooling machine in which all these problems are solved in unison the thread passing round a movable 25 guide member which under the tension of the thread on the one hand for obtaining a constant thread tension controls the brake of the delivery reel or spool and on the other hand causes the brake to operate when 30 the thread is finished or breaks, so that the delivery spool or reel is prevented from running further, and moreover operates the stopping device of the wind up spool to stop instantly the winding up and further- 35 more disconnects the spool spindle in the moment when on account of a disturbance of the free delivery of the thread from the storage spool or reel the thread tension exceeds a certain amount. The uniform ac- 40 tion of the reel or spool brake and the quick and reliable action of the stopping de- 45 vice make the invention especially useful for shed spool machines.

In the accompanying drawings—

Fig. 1 shows diagrammatically a front view of a jack-frame according to the invention.

Fig. 2 is a side view and

Fig. 3 shows an arrangement of the stop- 50 ping device suitable in case delivery reels are used instead of storage spools.

The delivery spools *a* are journaled in the frames *r* of the delivery devices. Each thread leaving the spool is passed over a 55 thread guide *b* acting upon the brake of its spool in such a manner that it opposes

always the same resistance against the delivery of the thread. By the tension spring *f* each thread guide is kept under a power corresponding to the desired tension of the 60 thread.

The spools *a* are provided each with a brake disc *s* (Fig. 2) surrounded by a brake band. One end of each brake band is secured to the frame *r* and spring actuated 65 tension levers *h* act upon its free end. The shaft of each thread tensioning device is provided with a cam *e* which on lifting of the thread guide *b* presses against a brake releasing lever transferring the pressure to 70 the brake tensioning lever *h*, whereby the braking action is reduced and finally becomes null.

Fig. 2 shows the position of the thread 75 guide which it has during the spooling operation with small oscillations. By means of a rod *g* the thread guide is connected to the disengaging or stopping device in such a manner as to cause releasing of the thread guard *w* by a downward rocking which until now was realized directly by the thread as 80 soon as the storage spool emptied or the thread was broken whereby the stopping device becomes operative in known manner.

In order to cause each thread to follow 85 always its distinct separate course it is passed through a guide ear *l* arranged at suitable spots. In order that the thread may run over its guide arm always from the same point each thread is led first from 90 the storage spool or reel over the rock shaft of the thread guide, the remaining course is clearly shown in the drawings.

In the described jack-frame or spooling 95 machine no thread breaks by starting the spool spindle because each thread at once causes its delivery reel to start. Firstly the tensioned thread guide is lifted completely releasing the brake of the delivery reel which thereupon is capable of revolving as easily as the friction of its layers of thread allows so that its inertia only is to be overcome. On the other hand the brake instantly acts with its full power as soon as it is disengaged from thread guide accord- 100 ing to a reduction of the thread tension when the delivery reel is emptied or the thread breaks.

From the beginning to the end of the 110 spooling operation each thread has the ten- sion received by its guide arm. If the resistance of the delivery reel or spool in-

creases with the reduction of its diameter the brake simultaneously is further released correspondingly whereby the increased resistance of delivery is neutralized again.

5. The device represented in Fig. 3 stops the spooling machine also when the tension of the thread increases over a certain limit, for instance if the thread is prevented from running freely away from the reel. Then 10 the thread lifts its guide arm *b* and with it the rod *g* engaging the lever *w'*, which is coupled to a second releasing hook *w''*. The latter swings to the left and engages the constantly revolving toothed wheel *w'''* and 15 stops the machine in known manner. In this case the purpose of the thread guide *b* is also to prevent the thread from breaking.

I claim—

1. In a spooling machine, a thread guide, 20 a delivery spool, a stopping device, a brake acting upon the delivery spool, said guide controlling said brake in accordance with the tension of the thread and releasing the brake to act upon the delivery spool and 25 actuating the stopping device when the thread runs out or breaks.

2. In a spooling machine, a thread guide, a delivery spool, a brake acting upon the delivery spool, a stopping device, said guide 30 controlling said brake in accordance with the tension of the thread and releasing the brake to act upon the delivery spool and actuating the stopping device when the thread runs out or breaks, and means actuating 35 the stopping device when the tension

of the thread exceeds a predetermined limit.

3. In a spooling machine, a delivery spool, a thread guide, a brake acting upon the delivery spool, a stopping device, and means connecting said thread guide to said brake 40 and to said stopping device.

4. In a spooling machine, a delivery spool, a wind-up spool, a thread, a brake acting upon the delivery spool, a stopping device, and means controlled by the thread guide 45 adjusting said brake according to the tension of the thread and operating the stopping device when the thread runs out or breaks or the tension of the thread exceeds a predetermined limit.

5. In a spooling machine, a delivery spool, a wind up spool, a thread guide, a brake acting upon the delivery spool, a stopping device, a cam fixed to the thread guide controlling said brake, and means connecting 55 the thread guide to the stopping device.

6. In a spooling machine, a delivery spool, a thread guide, a brake acting upon the delivery spool, a stopping device, a cam fixed to the thread guide controlling said brake, 60 a rod connecting the thread guide to the stopping device, and means on said rod releasing the stopping device for operation when the thread runs out or breaks or the tension of the thread exceeds a predetermined limit.

In testimony whereof I have signed my name to this specification.

GUIDO HORN.
